Hooper & Shoups / ATTORNEYS.

UNITED STATES PATENT OFFICE

ANDREW W. LOVEJOY, OF KANSAS CITY, MISSOURI

WINDOW SCREEN

Application filed February 29, 1928. Serial No. 257,837.

This invention relates to window screens of that general class composed of metal corner sockets and side and end bars of wood or the like.

5 My object is to produce a strong and rigid construction belonging to the class mentioned, which can be economically and quickly assembled without the use of cross braces or any other stiffening or bracing accessories. A further object is to produce corner sockets in which the bars of the screen may be readily secured regardless of whether the ends of said bars are squared or mitered. A still further object is to provide sheet metal 15 corner sockets which tend to prevent water from gaining access to the extremities or raw ends of the bars of the frame so that the period of service of the latter shall be materially lengthened. Another object is to produce a screen which can be manufactured and sold in quantity at an appreciably lower figure than the conventional type of wood screen in which the bars at the corners are mortised and nailed or dove-tailed together, and 20 a still further object is to provide frame parts which can be conveniently assembled in bundles for economy in shipment.

With these general objects in view, the invention consists in certain novel and useful 30 features of construction and combination of parts as hereinafter described and claimed; and in order that it may be fully understood reference is to be had to the accompanying drawing, in which:

35 Figure 1 is an outer face view of a window screen embodying the invention.

Figure 2 is a full size elevational view of one corner of the screen as viewed from the inner side thereof.

40 Figure 3 is a section taken on the line III—III of Figure 2.

Figure 4 is a perspective view of one of the corner sockets of the screen.

Figure 5 is a reduced view of a blank from 45 which a corner socket is produced.

Referring now to the drawing in detail, and particularly to the socket feature of the screen to be die formed from sheet metal,

1 indicates a right-angle shaped body, the 50 arms thereof being identified by the charac-

ters 2 and 3. At the inner angle of the body is a correspondingly shaped but narrower extension bisected diagonally to provide similar flanges 4 and 5 for the arms 2 and 3 respectively, said flanges 4 and 5 being adapted 55 to be bent along the junction lines thereof with the arms 2 and 3, to stand at right-angles to said arms and form inner edges or walls for the socket.

The body portion is provided at the opposite side from flange or wall 4, with an extension in width corresponding to the combined widths of arm 2 and flange 4, and said extension on the dotted line 6 paralleling arm 2, is adapted to be folded to provide an outer 60 edge or wall 7 and an inner side wall 8 for the socket, the end of the wall 8 opposite the arm 3 being of arcuate form as at 9 and extending angularly between points in line with the outer corner and inner corner of body 65 portion 1.

At the opposite side of arm 3 from flange or wall 5, the body portion is provided with an extension equal in width to the combined widths of arm 3 and flange or wall 5, and 70 said extension is adapted to be folded on the dotted line 10 to provide an outer edge wall 11 and an outer side or face wall 12, and the last-named wall is diagonally bowed at one end as at 13 in the same manner as described 75 with reference to the bowed or arcuate end 9, and the wall 11 between the adjacent arcuate ends 9 and 13, is formed with a foldable extension lug 14.

Wall 8 is provided at the opposite side 80 thereof from wall 7, with an oblong rectangular extension 15 adapted to form an inner wall and eventually fit flatly against wall 4, and said extension or wall 15 is provided at the end adjacent the arcuate end 9 of wall 8, with an extension lug 16, and near its other end with an extension lug 17, the lug 17 extending laterally at right angles to lug 16. Wall 12 is provided at its opposite edge from wall 11 with an oblong rectangular extension 18, provided at its end adjacent its arcuate end 13 with a lug 19, and near its other end with a laterally-projecting lug 20.

To fold the blank described so as to produce a corner socket, arms 4 and 5 are folded 100

along the inner margin of the arms 2 and 3 respectively to positions at right angles to the body portion, see dotted lines Figure 5. The blank is then folded at the junction of arm 2 and wall 7 until the latter stands at right-angles to the body portion and parallel with the folded arm 4. The extension is then bent along the dotted line 6 until portion 8 stands in parallel relation to the body portion. At the junction of portion 8 and portion 15 another fold in the same general direction is made so that portion 15 shall enclose and fit flatly against arm 4, it being necessary however before this last fold is made, to first fold lug 16 at right angles to portion 15, so that when the latter is folded as explained, the lug 16 shall enclose and fit flatly against the folded flange 5. After the portion 15 has been arranged as explained, the lug 17 is folded so as to fit flatly against the arm 2 of the body portion, thus completing one arm of the socket.

The manipulation described with reference to portions 7, 8, 15 and lugs 16 and 17, is followed with respect to portions 11, 12, 18, and lugs 19 and 20, it being noted that lug 19 is like lug 16, bent at right-angles to portion 15, so as to enclose and fit at the inner side of arm 15 before the portion 18 can be caused to enclose and overlap the arm 5, it being noted that when the folds are completed the lug 16 is interposed between flange 5 and arm 18, and that lug 19 is fitting against the opposite side of arm 15 from arm 4, thus completing the other arm of the corner socket. It will be seen that at the inner corners of the socket, the material is of three-ply or thickness to impart great strength and rigidity, and that the inner edge walls of the socket are of double strength. At the outer corner of the socket where the ends of the walls 11 and 7 come together in the folding operation, the lug 14 is bent over the adjacent end of wall 7 so as to close said joint and stiffen the corner. At the side which is preferably termed the outer face, the bowed ends 9 and 13 of portions 7 and 12 are in overlapping relation, the bowed end 13 overlapping the bowed end 9, it being noted by reference to Figure 1 that the corner sockets can be so arranged that the overlapping bowed ends 13 shall always face in a downward direction tending to shed water running down or beating upon the screen, so that such water shall be prevented from entering the socket between said overlapping bowed portions.

The blanks of the type described may be folded by hand, but it is contemplated that they shall be folded automatically, as by the use of forming dies the folding operations can be accomplished with greater accuracy and of course with far greater rapidity and economy.

Referring now to Figures 1 to 3 inclusive, A represents the sides or bars of a screen

frame, said bars being fitted at their ends in the sockets. When thus fitted, it is desirable that nails shall be driven through the various exposed lugs 14, 17, 19 and 20, and the interposed parts of the socket into the frame bars, and to insure the most effective placing of the nails, the sockets are provided with holes for nails B for uniting the sockets with the bars, which nails will prevent the various lugs from being readily sprung or pressed out by catching on other objects in handling and in shipment. The nails furthermore make the frame perfectly rigid by guarding against any possibility of the frame spreading more at one end or side than at the opposite end or side, as each socket is nailed at one or more points to the adjacent ends of two of the bars and thus unite all of the bars together as a unitary or integral structure. It is obvious of course, that the nailing operation can be performed without providing holes in the blank, as the metal is thin and can be readily punctured by the nails as the latter are applied and that with proper metal and equipment the lugs and other overlapping parts can be so accurately bent and applied that the nailing operation can be dispensed with entirely.

When the skeleton frame composed of the bars and sockets is completed, screening material C is placed upon the frame and tacked or otherwise secured thereto, and to provide a finish for the frame by covering the raw edges of the gauze, and to assist in holding the latter in place, batten strips D are fitted over the marginal portions of the gauze and tacked in place as conventional in screen practice.

In Figure 2 it will be noted that the ends of juxtaposed bars A are shown as mitered at their meeting edges in full lines and as having squared ends in dotted lines. For economy and equal efficiency the squared ends are preferred, especially for screens which are to be shipped in knocked-down condition, as the squared ends are less susceptible to injury than bevelled ends, and it is contemplated that the four sides and four batten strips for each screen, shall be tied together in a bundle for shipping purposes. Screening material may be shipped in a roll or may be obtained locally by the purchaser so as to avoid the expense of shipment of the screen material. Associated with each bundle of bars and battens will be one set of corner sockets which by preference will be shipped in completed form and ready for the reception of the bars to be applied by the purchased, if desired, as anyone can assemble the parts of a screen of this character properly and easily, the only point on which instructions may be needed, being to suggest that it is preferable to arrange the four corner sockets so that the arcuate

ends hereinbefore mentioned shall be at the outside of the screen with the overlapping arcuate end portions facing downward to facilitate the shedding of water, as hereinbefore mentioned.

It will be noted by comparison of Figures 2 and 4, that in the former the lug 16 is against the exposed side of edge wall portion 18, and lug 19 is between edge wall portions 4 and 15, and that in Figure 4, lug 19 is against the exposed side of portion 15 and lug 16 between the portions 5 and 18. This difference in the folding operation is resorted to so that when the four corner sockets are assembled 15 in proper relative position the overlapping arcuate edges shall all be at the outer side of the screen as shown by Figure 1, and face to prevent water flowing downward from entering between said overlapping portions. 20 This also results in disposing the flanges 14 of the two upper sockets, in a depending position and the flanges of the right-hand socket of the lower pair in a horizontal position under the said sockets, the flange 14 of 25 the left-hand lower socket extending upward.

It is obvious of course, that all of the sockets may be identical in all respects, but that in such case, it will result that two sockets of each set will have their sides 2-3 at the 30 outer face of the screen and the other two at the inner face of the screen; this arrangement being undesirable as detracting from the appearance of the screen if closely scrutinized.

From the above description, it will be apparent that I have produced a screen which embodies the features of advantage set forth as desirable in the statement of the objects 40 of the invention, and which is susceptible of modification in minor particulars without departing from the principle of construction and mode of operation involved or from the spirit and scope of the appended claims.

I claim:

1. A corner socket for screen frames, composed of two angularly disposed tubular arms, the inner edges of the arms overlapping to provide inner edge walls of double thickness, the end of one of said overlapping portions of each edge wall being provided with a lug at the inner corner of the socket, the lugs standing at right-angles to each other and one of them being interposed between the two overlapping portions forming one of the 55 inner edge walls, and the other lug fitting against the exposed side of one of the overlapping portions forming the inner edge wall of the other arm of the socket.

2. A corner socket for screen frames, composed of two angularly disposed tubular arms, the inner edges of the arms overlapping to provide inner edge walls of double thickness, each outside portion of said inner edge walls having a lug extending at right-angles 65 from the free side edge of such portion and

fitting flatly against the adjacent side or face of the respective tubular arm of the socket.

3. A corner socket for screen frames, composed of two angularly disposed tubular arms, the inner edges of the arms being overlapping to provide inner edge walls of double thickness, the end of one of said overlapping portions of each edge wall being provided with a lug at the inner corner of the socket, the lugs standing at right-angles to each other and one of them being interposed between the two overlapping portions forming one of the inner edge walls, and the other lug fitting against the exposed side of one of the overlapping portions forming the inner edge wall of the other arm of the socket; each outside portion of said inner edge walls having a lug extending at right-angles from the free side edge of such portion and fitting flatly against the adjacent side or face of the respective tubular arm of the socket.

4. A corner socket for screen frames made of single piece of sheet metal and comprising a right-angle shaped side or face and a corresponding parallel face spaced therefrom and having overlapping arcuate ends extending diagonally from the inner angle to the outer angle of the socket; outer edge walls uniting the outer edges of said side or face portions and forming a joint at the outer corner of the socket, one of the said edge walls having an angularly-projecting lug bridging the said joint and fitting flatly upon the other edge wall, and edge walls at the inner corner of the socket paralleling the said outer edge walls.

5. A corner socket for screen frames made of a single piece of sheet metal and comprising a right-angle shaped side or face and a corresponding parallel face spaced therefrom and having overlapping arcuate ends extending diagonally from the inner angle to the outer angle of the socket; outer edge walls uniting the outer edges of said side or face portions and forming a joint at the outer corner of the socket, one of the said edge walls having an angularly-projecting lug bridging the said joint and fitting flatly upon the other edge wall, and inner edge walls paralleling the outer edge walls respectively, and each consisting of overlapping portions projecting respectively from the opposite face walls.

6. A corner socket for screen frames made of a single piece of sheet metal and comprising a right-angle shaped side or face and a corresponding parallel face spaced therefrom and having overlapping arcuate ends extending diagonally from the inner angle to the outer angle of the socket; outer edge walls uniting the outer edges of said side or face portions and forming a joint at the outer corner of the socket, one of the said edge walls having an angularly-projecting lug bridging

the said joint and fitting flatly upon the other edge wall, and inner edge walls paralleling the outer edge walls respectively and each consisting of overlapping portions projecting respectively from the opposite face walls; 5 said inner edge walls having laterally-projecting lugs at their free edges respectively overlapping the adjacent face or side walls of the socket.

10 7. A corner socket for screen frames made of a single piece of sheet metal and comprising a right-angle shaped side or face and a corresponding parallel face spaced therefrom and having overlapping arcuate ends 15 extending diagonally from the inner angle to the outer angle of the socket; outer edge walls uniting the outer edges of said side or face portions and forming a joint at the outer corner of the socket, one of the said 20 edge walls having an angularly-projecting lug bridging the said joint and fitting flatly upon the other edge wall, and inner edge walls paralleling the outer edge walls respectively and each consisting of overlapping portions projecting respectively from the opposite face 25 walls; said overlapping portions of the inner edge walls being provided at their adjacent ends with end lugs, one fitting between the overlapping portions of the edge walls of the 30 opposing socket arm, and the other fitting flatly against the exposed side of the outer portion forming the inner edge wall of the other arm of the socket.

8. A corner socket for screen frames made 35 of a single piece of sheet metal and comprising a right-angle shaped side or face and a corresponding parallel face spaced therefrom and having overlapping arcuate ends 40 extending diagonally from the inner angle to the outer angle of the socket; outer edge walls uniting the outer edges of said side or face portions and forming a joint at the outer corner of the socket; one of the said edge walls having an angularly-projecting lug bridging 45 the said joint and fitting flatly upon the other edge wall, and inner edge walls paralleling the outer edge walls respectively and each consisting of overlapping portions projecting respectively from the opposite face walls; 50 said inner edge walls having laterally-projecting lugs at their free edges respectively overlapping the adjacent face or side walls of the socket; and said overlapping portions of the inner edge walls being provided at their 55 adjacent ends with end lugs, one fitting between the overlapping portions of the edge wall of the opposing socket arm, and the other fitting flatly against the exposed side of the outer portion forming the inner edge wall 60 of the other arm of the socket.

9. A window screen corner comprising tubular arms extending at right angles to each other and each of rectangular cross section, the structure being made from a single piece 65 of sheet metal, and being provided at the

inner corner formed at the junction of the arms, with a pair of lugs extending at right angles to each other and forming re-inforcements for said inner corner, and also having a lug extending around and bracing the 70 outer corner formed by said arms.

In testimony whereof I affix my signature.

ANDREW W. LOVEJOY.
